BRACELET OR SIMILAR ARTICLE

Herman Bogoff, Chicago, Ill.

Application February 1, 1950, Serial No. 7,629

Term of patent 7 years

(Cl. D45—4)

To all whom it may concern:

Be it known that I, Herman Bogoff, a citizen of the United States, residing at Chicago, in the county of Cook and State of Illinois, have invented a new, original, and ornamental Design for a Bracelet or Similar Article, of which the following is a specification, reference being had to the accompanying drawing, forming part thereof, wherein—

Fig. 1 is a plan view of a bracelet or similar article showing my new design; and

Fig. 2 is a side elevation thereof.

The links outlined in dot and dash lines are duplicates of those shown in full lines. The dominant features of my design reside in the portions of the jeweled links shown in full lines, the two large, jeweled links at the right hand end being repeated alternately throughout the length of the bracelet as indicated by the links shown in dot and dash lines.

I claim:

The ornamental design for a bracelet or similar article, as shown and described.

HERMAN BOGOFF.
